UNITED STATES PATENT OFFICE.

ANTHONY S. CONTI, OF CHICAGO, ILLINOIS, ASSIGNOR OF THIRTY-FIVE ONE-HUNDREDTHS TO MORTON A. LEA AND THIRTY ONE-HUNDREDTHS TO CHARLES V. JEWELL, BOTH OF CHICAGO, ILLINOIS.

PNEUMATIC SANDER.

1,160,852.

Specification of Letters Patent. Patented Nov. 16, 1915.

Application filed April 12, 1915. Serial No. 20,873.

To all whom it may concern:

Be it known that I, ANTHONY S. CONTI, a citizen of the United States, and a resident of the city of Chicago, county of Cook, 5 and State of Illinois, have invented certain new and useful Improvements in Pneumatic Sanders, of which the following is a specification.

My invention relates to improvements in 10 pneumatic sanders especially adapted for use on railroad locomotives for sanding the tracks of the railroad, and has for its object the provision of an improved construction of this character which is simple and efficient in use.

The invention consists in the combinations and arrangements of parts hereinafter described and claimed.

The invention will be best understood by 20 reference to the accompanying drawings forming a part of this specification, and in which,

Figure 1 is a horizontal section through the lower portion of an ordinary sand box 25 equipped with means embodying my invention, showing parts of said means in top plan view and other parts in horizontal section, Fig. 2, a horizontal section taken on substantially line 2—2 of Fig. 1, Fig. 3, a face view of the sand applying attachment shown partially in section, Fig. 4, a section 30 on line 4—4 of Fig. 3, and Fig. 5, a section on line 5—5 of Fig. 3.

The preferred form of construction as 35 illustrated in the drawings comprises a body 6 adapted to be secured by means of bolts 7 to the side of a sand box 8 as indicated in Fig. 1. The sand box 8 is provided with two horizontal discharge passages 9 registering with corresponding passages 10 in 40 body 1. Arranged just outside of each of the passages 10 is a horizontal discharge passage 11 parallel therewith and connected therewith by means of a transverse horizontal passage 12 as indicated. Arranged in each of the discharge passages 11 is an air nozzle 13 adapted to project a blast of air outwardly through said passage into a discharge pipe 13' leading therefrom. The 45 inner end of nozzle 13 opens into an air supply chamber 14 supplied with compressed air through a supply pipe 15 and equipped with a strainer plate 16 adapted

to strain the air as it passes through said nozzle.

Atmospheric air is admitted to the upper portion of each of the passages 10 through an unobstructed air supply pipe 17 extending upwardly therefrom and having its upper end turned downwardly and inwardly 60 as shown to prevent the entry of rain or other flying particles therein. The discharge pipe 13' is connected with the usual sand supply pipe (not shown) as will be readily understood. In use when it is desired to supply sand to either of the sand supplying pipes of the locomotive air is admitted to the corresponding pipe 15 which projects a blast outwardly through a discharge pipe 13' to effect a discharge of the sand therethrough. Owing to the fact that the passage leading to the discharge passage is horizontally arranged the flow of sand is automatically discontinued upon discontinuance of the supply of air. This use of 75 the compressed air is largely a suction action through the passages 12, 10 and 9. I have found from experience that there is a tendency for the sand to clog or choke in this passage. To prevent this clogging or choking I have provided the air inlet pipe 17 in the supply passage leading to the discharge which admits atmospheric air to the upper portion thereof above the sand therein and this supply of air so provided at the 80 point specified practically eliminates this 85 tendency to clog and choke in the supply passage.

While I have illustrated and described the preferred form of construction for carrying 90 my invention into effect, this is capable of variation and modification without departing from the spirit of the invention. I, therefore, do not wish to be limited to the precise details of construction set forth, but 95 desire to avail myself of such variations and modifications as come within the scope of the appended claims.

Having described my invention what I claim as new and desire to secure by Letters 100 Patent is:

1. A sander comprising a body provided with a discharge passage; a nozzle directed into said discharge passage; a horizontally arranged supply passage leading to said 105 discharge passage and nozzle; unobstructed

means for admitting air into the upper portion of said supply pipe; and means for supplying fluid under pressure to said nozzle, substantially as described.

5. 2. A sander comprising a body provided with a discharge passage; a nozzle directed into said discharge passage; a horizontally arranged supply passage leading to said discharge passage and said nozzle; means for admitting air into said supply passage, said means comprising an unobstructed pipe projecting upwardly therefrom and having its upper end turned downwardly; and means for supplying fluid under pressure to said nozzle, substantially as described.
- 10 3. A sander comprising a sand box provided with a horizontal discharge passage; a body secured to said box and provided with

a horizontal passage registering with said discharge passage; a horizontal passage in 20 said body parallel with the first mentioned passage therein; a lateral horizontal passage in said body connecting said parallel passages; and an unobstructed air pipe leading into the upper portion of said first mentioned passage in said body, said pipe having its upper end turned downwardly, substantially as described.

In testimony whereof I have signed my name to this specification in the presence of 30 two subscribing witnesses.

ANTHONY S. CONTI.
